UNITED STATES PATENT OFFICE.

HOWARD GEORGE WALKER, OF LA GRANGE, AND ALBERT THOMAS MARCH, OF WESTERN SPRINGS, ILLINOIS, ASSIGNEES TO WESTERN ELECTRIC COMPANY, INCORPORATED, OF NEW YORK, N. Y., A CORPORATION OF NEW YORK.

MECHANISM FOR WORKING PULPOUS MATERIAL.

Application filed May 8, 1924, Serial No. 711,996. Renewed October 20, 1928.

This invention relates to improvements in mechanism for working pulpoous material, and more particularly to mechanism for forming such material to constitute a homogeneous coating for cores in strand form, such as wire and the like.

Mechanisms made in accordance with this invention are particularly well adapted for use in connection with the method and apparatus for coating cores disclosed in the co-pending application of H. G. Walker, Serial No. 621,242, filed February 26, 1923, but it is to be understood that the invention is not limited to such use, but only in so far as is defined by the appended claims.

The primary object of the invention is to provide a forming mechanism of simple and substantial construction.

Another object of the invention is to provide a forming mechanism which will operate upon the pulpoous material so as to form it into a homogeneous and uniform coating.

A further object of the invention is to provide a forming mechanism which may be operated at high speed and will not strip the coating material from the core during the forming operation.

A forming mechanism embodying the invention comprises a plurality of collars held together in spaced relation by a plurality of rods. The collars are adapted to accommodate a traveling core to which pulpoous material has been applied. A member held against displacement relative to the collars and a resilient member mounted upon one of the collars co-act to work the pulpoous material into a coating which conforms to the shape of the core, when the forming mechanism is rotated around an axis coincident with the axis of the core.

Other objects of the invention will become apparent as the detail description progresses, reference being had to the accompanying drawing, wherein

Fig. 1 is a central longitudinal section taken through a forming mechanism embodying the invention;

Fig. 2 is a section taken on line 2—2 of Fig. 1;

Figs. 3 and 4 are transverse sectional views taken on lines 3—3 and 4—4, respectively, of Fig. 1;

Figs. 5 and 6 are enlarged sectional views

illustrating the manner in which the pulp is applied to the core before it is delivered to the forming mechanism, and

Figs. 7 and 8 are enlarged sectional views showing the forming of a pulp coating during the forming operation and after the completion of the forming operation, respectively.

The forming mechanism shown in the accompanying drawing is especially adapted to operate in conjunction with apparatus shown in the aforementioned application of H. G. Walker, Serial No. 621,242, filed February 26, 1923, which apparatus is adapted to apply pulpoous material to a core and comprises a foraminous member and then an additional amount of pulpoous material is deposited upon the core and the foraminous container. The pulp, so deposited, and the core are then brought into contact with one of the squeezing rolls which cooperates with the foraminous member to squeeze out the "free liquid", so to speak, in the pulp coating. The partially dried pulp adheres to the felt of the squeezing roll in the form of a ribbon with the core substantially centrally located therein as shown in Fig. 5 of the accompanying drawing, and the core with the pulp ribbon attached thereto passes around the roll and between it and its cooperating roll, the contour imparted to the ribbon by the squeezing rolls being shown in Fig. 6.

The forming mechanism embodying the features of the present invention is designed to receive the core and its ribbon from the squeezing rolls and to wrap the projecting edges of the ribbon around the core and around each other until it conforms substantially to the shape of the core. The appearance of the coating after it is first acted upon by the forming mechanism is shown in Fig. 7, and the appearance thereof after the forming action is completed is shown in Fig. 8.

Referring to the drawings, the forming mechanism comprises a plurality of collars 10 and 11 held together in spaced relation by means of rods 12. Integral with each of the collars 10 and 11 is a sleeve 13 and 14, respectively, the sleeves 13 and 14 being rotatably mounted in suitable bearings 15 and 16. A pulley (not shown) may be se-

cured to either of the sleeves 13 and 14 to provide means for driving the forming mechanism. A plate 17 interposed between the collars 10 and 11 has one of its ends 5 rigidly secured to the collar 10 by means of a plurality of screws 18, the other end of the plate being rigidly secured to the collar 11 by means of a plurality of screws 19. A resilient plate 20 disposed in opposed relation to the plate 17 has one of its ends rigidly secured to the collar 10 by a plurality of screws 21, the other end of the plate 20 being free and tending to spring into engagement with the plate 17. As shown in 10 Fig. 1, the plates 17 and 20 are adapted to receive a core 22 carrying a ribbon 23 of pulposous material. This core with its ribbon of pulposous material may be supplied by any suitable apparatus, such as for instance 15 the apparatus shown in the copending application of H. G. Walker, Serial No. 621, 242, filed February 26, 1923. The core is advanced through the collar 10 and the pulposous material carried by it is engaged by 20 the plates 17 and 20, which wrap the projecting edges of the ribbon around the core and around each other until it conforms substantially to the shape of the core as shown 25 in Fig. 8. The ends of the plates 17 and 20 which first receive the core and its ribbon 30 are flared outwardly so as to gradually wrap the edges of the ribbon around the core without stripping it from the core, the appearance 35 of the coating after it has been acted upon by the flared ends of the plates being shown in Fig. 7. Of course, it is understood 40 that the forming mechanism is rotated rapidly around the coated core and the ribbon during the forming operation.

40 It will be noted that the major portion of the plate 17 is disposed substantially parallel to the path of the core and that the plate 20 functions as a forming member as it presses the pulp covered core against 45 the plate 17. However, in the preferred embodiment of the invention, the plate 17 is spaced from the axis of rotation of the collars 10 and 11 a distance substantially equal to one-half of the diameter of the 50 finished article produced by the forming mechanism. Therefore, the plate 17 tends finished article produced by the forming coating.

55 It will also be noted that the collars 10 and 11, together with the spacing rods 12, constitute a carrier for the plates 17 and 20, the plate 17 being secured against displacement relative to the carrier, and the plate 20 being mounted in the carrier, but being 60 adapted to function as a pressure member.

What is claimed is:

1. In a mechanism for working pulposous material on a core, a member engaging said material and secured against displacement 65 toward or away from the core, and a form-

ing member engaging said material, the forming member being rotatable around the core.

2. In a mechanism for working pulposous material on a core, a member engaging said material and secured against displacement 70 toward or away from the core, and a forming member engaging said material, the members being rotatable around the core.

3. In a mechanism for working pulposous material on a core, a member engaging said 75 material and secured against displacement toward or away from the core, and a pressure member engaging said material, one of the members being rotatable around the core.

4. In a mechanism for working pulposous material on a core, a member engaging said material and secured against displacement 85 toward or away from the core, and a pressure member engaging said material, the members being rotatable around the core.

5. In a mechanism for working pulposous material on a core, a member engaging said material and secured against displacement 90 toward or away from the core, and a resilient member engaging said material, said members being rotatable around the core.

6. In a mechanism for working pulposous material on a core, a member engaging said material and secured against displacement 95 toward or away from the core, and a pressure member engaging said material and disposed in opposed relation with respect to the first-mentioned member, the members being rotatable around the core.

7. In a mechanism for working pulposous material on a core, a member engaging said material and secured against displacement toward or away from the core, and a pressure member engaging said material and disposed in opposed relation with respect to the first-mentioned member, the members being 100 rotatable around a common axis to shape the material around the core.

8. In a mechanism for working pulposous material on a core, a member slidably engaging said material and secured against displacement toward or away from the core, and a pressure member slidably engaging 110 the material and cooperating with the first-mentioned member to shape said material so that it conforms to the core.

9. In a mechanism for working pulposous material on a core, a member slidably engaging said material and secured against 120 displacement toward or away from the core, and a resilient member slidably engaging said material and cooperating with the first-mentioned member to shape said material so that it conforms to the core.

10. In a mechanism for working pulposous material on a core, a member slidably engaging said material and secured against displacement toward or away from the core, and a pressure member slidably engaging 130

the material and disposed in opposed relation with respect to the first-mentioned member.

11. In a mechanism for working pulpous material on a core, a member slidably engaging said material and secured against displacement toward or away from the core, and a resilient member slidably engaging the material and disposed in opposed relation with respect to the first-mentioned member.

12. In a mechanism for working pulpous material on a core, a member slidably engaging the material and secured against displacement toward or away from the core, and a pressure member slidably engaging said material and disposed in opposed relation with respect to the first-mentioned member, the members being rotatable around the core.

13. In a mechanism for working pulpous material on a core, a member slidably engaging the material and secured against displacement toward or away from the core,

and a resilient member slidably engaging 25 said material and disposed in opposed relation with respect to the first-mentioned member, the members being rotatable around the core.

14. In a mechanism for working pulpous 30 material on a core, a carrier rotatable around the core, a member secured against displacement relative to the carrier and disposed to engage said material, and a pressure member mounted in the carrier and disposed to 35 engage said material.

15. In a mechanism for working pulpous material on a core, a carrier rotatable around the core, a member secured against displacement relative to the carrier and disposed 40 to engage said material, and a resilient member mounted in the carrier and disposed to engage said material.

In witness whereof, we hereunto subscribe our names this 29th day of April, A. D. 45 1924.

HOWARD GEORGE WALKER.
ALBERT THOMAS MARCH.
